US0D1021067S

(12) **United States Design Patent** (10) **Patent No.:** **US D1,021,067 S**
(45) **Date of Patent:** **** Apr. 2, 2024**

(54) **INHALER**

(71) Applicant: **Consort Medical Limited**, King's Lynn (GB)

(72) Inventor: **Adam Gibbons**, King's Lynn (GB)

(73) Assignee: **Consort Medical Limited**, King's Lynn (GB)

(**) Term: **15 Years**

(21) Appl. No.: **29/854,526**

(22) Filed: **Sep. 26, 2022**

(30) **Foreign Application Priority Data**

Apr. 8, 2022 (EM) 008931117-0001

(51) **LOC (14) Cl.** **29-02**

(52) **U.S. Cl.**

USPC **D24/110**

(58) **Field of Classification Search**

USPC D24/107, 108, 110, 110.5, 127, 164

(57) **CLAIM**

The ornamental design for an inhaler, as shown and described.

DESCRIPTION

FIG. 1 is a perspective view of an inhaler showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings illustrate portions of the article and form no part of the claimed design.

1 Claim, 4 Drawing Sheets
